(57) **CLAIM**

The ornamental design for a front wheel arch for a vehicle, as shown and described.

DESCRIPTION

FIG. 1 is a front right perspective view of a front wheel arch for a vehicle according to the present invention.

FIG. 2 is a front left perspective view of the front wheel arch shown in FIG. 1.

FIG. 3 is a rear left perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front view of the front wheel arch shown in FIG. 1-10, but with the front wheel arch mounted on a front left portion of the vehicle, as viewed from the driver's perspective, and the rest of the vehicle shown in de-emphasized and half-tone portions so as to illustrate environmental structure. These portions form no part of the claimed invention. More particularly, in FIG. 11, the inventive front wheel arch is shown within the broken line, and the elements shown outside the broken line form no part of the claimed invention, but are instead included to show environmental aspects thereof. The invention further contemplates a mirror image front wheel arch located on a front right portion of the vehicle.
